UNITED STATES PATENT OFFICE.

ARTHUR A. BACKHAUS, OF BALTIMORE, MARYLAND, ASSIGNOR TO U. S. INDUSTRIAL ALCOHOL CO., A CORPORATION OF WEST VIRGINIA.

LIQUID FUEL.

1,324,765.

Specification of Letters Patent. Patented Dec. 9, 1919.

No Drawing.

Application filed November 28, 1917. Serial No. 204,379.

To all whom it may concern:

Be it known that I, ARTHUR A. BACKHAUS, of Baltimore, in the State of Maryland, have invented a certain new and useful Improvement 5 in Liquid Fuel, (Case 10,) and do hereby declare that the following is a full, clear, and exact description thereof.

My invention relates particularly to fuels designed to be used in any desired manner, 10 but it has application especially to fuels adapted to be used as a source of power, as for example, fuels for burners and motor fuels.

The object of my invention is to provide 15 a fuel containing a petroleum hydrocarbon, as well as alcohol, and an ingredient adapted to blend the same or form a solution with the hydrocarbon and alcohol.

A further object of my invention is to provide 20 a fuel of this character, which is of such a nature that only a very small quantity of the third ingredient is found necessary.

A further object is to provide a fuel of 25 this character which contains a large percentage of the petroleum hydrocarbon, notwithstanding the small percentage of the third ingredient.

A further object of my invention is to provide 30 a fuel of this character in which the third ingredient is carbon disulfid and to provide a fuel which is free from constituents which are oxidizable by the air at normal temperatures.

Further objects of my invention will appear 35 from the detailed description thereof contained hereinafter.

While my invention is capable of being carried out in different ways, for the purpose 40 of illustration I shall describe only certain ways of carrying out the same herein.

For example, a fuel made in accordance with my invention may be comprised of:—

25 parts by volume of ethyl alcohol,

25 parts by volume of gasolene,

45 8 parts by volume of carbon disulfid.

While I have described my invention above in detail, I wish it to be understood that many changes may be made therein without departing from the spirit thereof.

I claim:

1. A completely blended fuel comprising a petroleum distillate and an alcohol, said petroleum distillate and alcohol being blended mainly by a quantity of carbon disulfid present in the fuel.

2. A completely blended fuel comprising gasolene and an alcohol, said gasolene and alcohol being blended mainly by a quantity of carbon disulfid present in the fuel.

3. A completely blended fuel comprising 60 a petroleum distillate and ethyl alcohol, said petroleum distillate and ethyl alcohol being blended mainly by a quantity of carbon disulfid present in the fuel.

4. A completely blended fuel comprising 65 gasolene and ethyl alcohol, said gasolene and ethyl alcohol being blended mainly by a quantity of carbon disulfid present in the fuel.

5. A completely blended fuel comprising 70 substantially equal quantities of a petroleum distillate and an alcohol, said petroleum distillate and alcohol being blended mainly by a quantity of carbon disulfid present in the fuel.

6. A completely blended fuel comprising 75 substantially equal quantities of gasolene and an alcohol, said gasolene and alcohol being blended mainly by a quantity of carbon disulfid present in the fuel.

7. A completely blended fuel comprising 80 substantially equal quantities of a petroleum distillate and ethyl alcohol, said petroleum distillate and ethyl alcohol being blended mainly by a quantity of carbon disulfid 85 present in the fuel.

8. A completely blended fuel comprising 90 substantially equal quantities of gasolene and ethyl alcohol, said gasolene and ethyl alcohol being blended mainly by a quantity of carbon disulfid present in the fuel.

In testimony that I claim the foregoing I have hereunto set my hand.

ARTHUR A. BACKHAUS.

Witnesses:

ERNEST J. WINTER,

WALTER T. SCHREIBER.
